UNITED STATES PATENT OFFICE.

WALTER C. BECKWITH, OF FOSTORIA, OHIO.

APPARATUS FOR RAISING SUNKEN VESSELS.

1,268,082.

Specification of Letters Patent. Patented June 4, 1918.

Application filed October 19, 1917. Serial No. 197,392.

To all whom it may concern:

Be it known that I, WALTER C. BECKWITH, a citizen of the United States, residing at Fostoria, in the county of Seneca and State of Ohio, have invented certain new and useful Improvements in Apparatus for Raising Sunken Vessels; and I do declare the following to be a full, clear, and exact description of the invention, such as will enable others skilled in the art to which it appertains to make and use the same, reference being had to the accompanying drawings and to the letters and figures of reference marked thereon, which form a part of this specification.

My invention relates to an apparatus for raising sunken vessels and its object is to provide, for the indicated purpose, an efficient means of great power and easy control.

To these ends my invention consists of the devices and construction hereinafter described, and illustrated in the accompanying drawings, in which—

Figure 1 is an end-view of my apparatus with parts broken away to disclose certain portion of the gears hereinafter mentioned, and Fig. 2, a top plan-view of the same with the roof shown in Fig. 1 removed, and with parts broken away to show portions of the gearing hereinafter referred to.

Like numerals of reference indicate like parts throughout the drawings.

In the drawing, 1—1 are elongated cylindrical pontoons, spaced apart a suitable distance and disposed in parallel relation. While, for illustration, I have in the present instance shown one pair of pontoons there may be as many pairs as may be required,— depending upon the length of the submerged object to be raised,—the members being disposed end to end and in alinement. The pontoons are of metal, are air-tight and are collectively of greater buoyancy than the object to be floated. Each of the pontoons is provided with an axial shaft, 2, upon the projecting ends of which are mounted and supported a stout framework 3 elevated above the water-line of the pontoons and extending across the space intervening between them. The journaled connections between the pontoons and their connecting frame permits the rotation of the pontoons. The framework 3 carries a deck 3^a upon which are hoisting engines 4

of any preferred type and, preferably, reversible. A boiler and steam connections for the engines are provided and need not be further described. Upon the shaft 5 of each of the engines 4 is a worm 6 which engages and drives a worm-wheel 7, fixed on the shaft of which is a sprocket-wheel 8. This sprocket-wheel drives an endless sprocket-chain 9 which in turn drives a sprocket-wheel 10 fixed upon or rigidly connected with the end of its pontoon. Upon each shaft 2 is a windlass or drum 11 upon which is wound a chain or cable which is engaged, by means of any suitable fastening device, with the vessel to be raised. Each sprocket-wheel 10 is provided with a ratchet-wheel 12 and a pawl 13, under the control of the operator through rods and levers 14, by means of which the drums may be held against accidental unwinding. This mishap is also guarded against by the worm-gears 6—7, but it will be understood that should it become necessary to pay out either cable 15 from its drum 11 in order to keep the submerged vessel on an even keel, this may be done by disengaging the pawl from its ratchet and by reversing the engine 4.

Through the deck of the structure is a large opening 16 giving access to the water and to the work between the pontoons.

The operation of my apparatus is as follows: The cables 15 being engaged with the sunken vessel at its opposite sides, with the pontoons disposed parallel with the sunken vessel and on opposite sides thereof, the engines are set in motion. Now through the worm-gear and the sprockets the pontoons are caused to rotate, carrying with them the windlasses 11 thus slowly but powerfully winding the cables upon the windlasses, and thus gradually lifting the sunken vessel to or near the surface so that the apparatus with its burden may be maneuvered into location and position for the convenient and final salvage of the vessel.

The construction illustrated in the drawings and described herein are given merely as one form of embodiment of my invention. Therefore I do not limit myself strictly to the mechanical details and relation of parts as shown since manifestly the same can be varied considerably without departing from the spirit of my invention as defined in the following claims. For example, the sprocket-wheel which carries

the drum 11 and the ratchet 12 may be made loose upon its shaft instead of being secured to the pontoon 1, though I prefer the arrangement already described, in which the 5 momentum of the turning pontoons may be made available.

Having described my invention, what I claim and desire to secure by Letters Patent, is:—

- 10 1. In an apparatus of the character described, a pair of elongated cylindrical pontoons having protruding axial shafts, a superstructure carried by said shafts and which holds said pontoons in parallel separated relation, drums on said protruding shafts, cables on the drums, driving means carried by the superstructure and connec-
- 15

Copies of this patent may be obtained for five cents each, by addressing the "Commissioner of Patents, Washington, D. C."

Witnesses:

GERTRUDE BRACKER,
J. H. JAMESON.

In testimony whereof I affix my signature in presence of two witnesses.

WALTER C. BECKWITH.
